UNITED STATES PATENT OFFICE.

JOHN ZANDER, OF CHICAGO, ILLINOIS.

GAS FURNACE.

1,406,713.

Specification of Letters Patent. Patented Feb. 14, 1922.

Application filed May 8, 1920. Serial No. 379,778.

To all whom it may concern:

Be it known that I, JOHN ZANDER, a citizen of the United States, residing at Chicago, in the county of Cook and State of Illinois, have invented certain new and useful Improvements in Gas Furnaces, of which the following is a specification.

My invention relates to improvements in gas furnaces.

10 The object of my invention is to provide a furnace of this character, which shall be more efficient than those used heretofore.

Contributory objects are to provide an improved furnace in which the incoming air and the gas meet and thoroughly mix just prior to entering the heating chamber, the air being preheated by the products of combustion; to provide a furnace of this type in which part of the products of combustion 20 pass directly to the outlet and the remainder pass over the walls of the preheating passages, the proportion thus employed for preheating purposes being under the control of the operator whereby the temperature of the 25 incoming air may be regulated accurately, and to provide a furnace in which a high temperature is maintained in the heating chamber with a reducing atmosphere, complete oxidization of the fuel taking place 30 after the burning fuel leaves the heating chamber, the heat of this further combustion being used in large part for preheating purposes and not wasted.

Other advantages will be apparent from 35 the more detailed description of the several embodiments of the invention illustrated in the drawings.

Figure 1 is a top plan view of a brass melting furnace.

40 Fig. 2 is a central sectional elevation thereof.

Fig. 3 is a front elevation.

Fig. 4 is a side elevation.

45 Fig. 5 is a section of a furnace of the open hearth type.

Fig. 6 is a longitudinal section thereof.

Fig. 7 is a section on the line 7—7 of Fig. 9 of a gas heated forge.

50 Fig. 8 is a section on the line 8—8 of Fig. 9.

Fig. 9 is a sectional elevation on the line 9—9 of Fig. 10.

Fig. 10 is a front elevation of said forge, and

Fig. 11 is a section on the line 11—11 of 55 Fig. 9.

The first form of furnace illustrated is referred to as a brass furnace, although it may be used for melting various other metals or alloys. It comprises a pair of suitable standards 1, 1, which support trunnions 2, 2, the latter being secured to opposite sides of the furnace shell 3. The furnace is adapted to rock about its trunnions to enable the contents to be poured. The shell is lined with 60 suitable refractory material 4, a melting chamber 5 being provided which is surrounded with this material. The fuel, which is preferably in the form of gas, is conducted to the furnace through a pipe 6 arranged 65 concentrically at the axis about which the furnace rocks, the gas flowing through a further pipe 7 and being delivered to the heating chamber, as shown in Fig. 2. The air is supplied from any suitable source through 70 a pipe 8 passing through the opposite trunnion and through a further pipe 9, which delivers it to a preheater preferably in the form of a casting having circular passageways 10 arranged concentrically with reference to the gas pipe 7. This preheater is heated by the products of combustion, as hereinafter described, and the incoming air 75 flows from one circular passage 10 to the passageway below it, through openings 11 80 located on opposite sides of the preheater, the air being caused to follow a circuitous course in order to increase its temperature effectively. The heated air then flows through a port 12 uniting with the gas above 85 the melting chamber. The port 12 is arranged somewhat tangentially with respect to the circular orifice through which the gas flows so that there is a thorough mixing of the two as they enter the combustion chamber.

The temperature in the melting chamber 5 is very much higher than the temperature due to combustion of the gas, by an amount represented by the initial preheating of the 100 air and hence of the mixture of air and gas prior to combustion. With this arrangement a high temperature may be maintained in the melting chamber, sufficient to melt brass pigs or other metal.

105 The products of combustion pass out through the outlet 13. The burning gas, as it flows to said outlet, passes one or more

orifices 14 through which air may be admitted to complete the combustion. The heat of this further combustion is not wasted, however, as the major portion of the products of combustion are caused to flow between and around the circular passageways 10, said products of combustion following circular passageways 15 formed by the walls of the preheater casting. The preheater is thus heated to a high temperature, the products of combustion, after passing the preheater, being ejected through the pipe 16, an air pipe 17 being connected thereto to provide an injector action which will draw the products of combustion over the preheater. A suitable valve 18 is provided (Figs. 1, 3 and 4) whereby the operator may vary the effectiveness of the air injector and thereby vary the proportion of the products of combustion, which flows over the preheater as compared with the proportion which flows through the outlet 13.

With the arrangement described, the incoming air may be suitably preheated without overheating or destroying the walls of the preheater. The preheated air may be preheated at least 1,000° F., which correspondingly raises the flame temperature. As a result a very high temperature is attained with a reducing flame.

In prior furnaces where preheating has been attempted, the preheater has necessarily been small to avoid overheating and destruction by the products of combustion, all of which were caused to flow past the preheater. In furnaces where no preheater has been employed, the products of combustion pass directly to the outlet at practically working temperature, thereby wasting an enormous quantity of heat. With my construction I not only provide a very high flame temperature without the disadvantage of an oxidizing atmosphere, but, I also provide means for utilizing practically all of the heat of combustion of the waste gases.

The furnace is charged through a suitable hinged door 19, the molten bath being poured from the furnace through a suitable spout 20 which is also closed during the melting operation by means of a suitable hinged plug or door 21 to prevent the admission of air and loss of heat through escape of partially burned gases.

The furnace shown in Figs. 5 and 6 is of the reverberatory type. It is provided with suitable refractory walls 30 and roof 31 and with a central partition 32 at one end. One of the side walls has an opening 33 or charging door. The air is admitted through a pipe 34 to the preheater 35, which is similar in general to the preheater previously described, the heated air passing out through an outlet 36 at which point it meets the gas which is admitted through the pipe 37.

65 Two such preheaters are preferably em-

ployed, one located on each side of the central partition 32. The gas and heated air mix with a rotary motion in the manner previously described and become thoroughly mixed as they pass through the ports 38 into the main chamber over the hearth. The burning gas circulates within the chamber and passes through an upper port 39 to the chamber 40 containing the preheater 35. The burning gas is, therefore, caused to flow down and around the preheater in a manner similar to that previously described. The products of combustion then pass downwardly and to the left, as shown in Fig. 5, and upwardly over the preheater in the opposite chamber 41 passing out through the pipe 42, the flow being regulated by means of the air injector 43, as previously described. Adjustable vents 44 are also provided to permit the escape of such products of combustion as are not drawn out by the injector.

The heating furnace illustrated in Fig. 7-11 inclusive is preferably of the type used to heat bars or rods preliminary to forging operations. The furnace in this case has suitable refractory walls 50 enclosing an upper chamber 51 and a lower chamber 52. Air is admitted through the pipe 53 and passes back and forth through a series of pipes 54 in the lower chamber, forming the preheater. The heated air then passes up through the pipe 55 flowing outwardly through the ducts 56 at which point it meets the incoming gas from the two pipes 57. The mixing is effected with a rotary motion as previously explained, the combined air and gas issuing from the ports 58 into the heating chamber 51. The burning gas flows to the opposite end of the chamber, then down through the vertical passageway 59 to the lower chamber 52, flowing over the preheater 54 and heating the same and thence through the outlet 60 to the injector 61 and outlet pipe 62. In this case also some of the burning gases escape through the opening 63, which is the opening through which are inserted the rods to be heated. The flame, which issues from the opening 63, heats the incoming gas in the pipes 64. In other words, either the air, the gas or both may be heated. The removable block 65 permits slag and other foreign matter to be scraped out of the heating chamber.

It will be noted in the first form of device that the preheater surrounds the burner whereby the products of combustion heat not only the preheater, but also heat the burner as well.

Although I have illustrated an air injector for causing the products of combustion to flow past the preheater, it is apparent that other means may be substituted for this purpose. In the various types of furnaces illustrated the means for causing the products of combustion to divide and flow in two

120 125 130

separate paths is located in the path which includes the preheater. It is evident, however, that said means may be located in the path which leads directly to the outlet, if desired, or in both paths. Various other changes may be made in the structure illustrated without departing from the invention as expressed in the appended claims.

What I claim is:—

- 10 1. In a furnace, the combination with a heating chamber, of a fuel supply therefor, an air preheater connecting with said fuel supply, a direct outlet for the products of combustion from said heating chamber, and a second outlet in communication with the space surrounding said preheater whereby part of the products of combustion pass over said preheater to heat the same.
- 20 2. In a furnace, the combination with a heating chamber, of a fuel supply therefor, an air preheater connecting with said fuel supply, a direct outlet for the products of combustion from said heating chamber, a second outlet in communication with the space surrounding said preheater whereby part of the products of combustion pass over said preheater to heat the same, and means for regulating the flow through one of said outlets.
- 30 3. In a furnace, the combination with a heating chamber, of a fuel supply connection and an air supply connection, means for admitting air to the burning fuel after it leaves the heating chamber to complete the combustion, means for drawing the products of combustion over the connection for the incoming air, and means for regulating the amount of the products of combustion thus employed.
- 40 4. A heating furnace having a heating chamber, an inlet port therefor, a gas pipe communicating with said port, an air preheater also communicating with said port by a tangential connection to insure mixing

of the air and gas, and an air injector arranged to draw the products of combustion over said preheater. 45

5. A heating furnace having a heating chamber, an inlet port therefor, a gas pipe communicating with said port, an air preheater also communicating with said port, and an air injector arranged to draw the products of combustion over said preheater. 50

6. A heating furnace having a heating chamber, an inlet port therefor, a gas pipe 55 communicating with said port, an air preheater also communicating with said port by a tangential connection to insure mixing of the air and gas, an air injector arranged to draw the products of combustion over 60 said preheater, and an additional outlet in direct communication with said heating chamber through which part of the products of combustion pass, the amount being regulated by said air injector. 65

7. The combination with a burner, of a preheater arranged concentric therewith and comprising a series of annular passages for air with annular passages between them for the products of combustion, whereby said 70 products of combustion surround and heat said burner.

8. In a heating furnace, a burner having an axially arranged fuel inlet and a tangentially arranged air inlet, for mixing said 75 fuel and air.

9. In a furnace, means for admitting fuel and air to the heating chamber, means for preheating one of said constituents to produce a high flame temperature in said chamber with incomplete combustion, and means for admitting additional air to said flame after it leaves said chamber to complete said combustion. 80

In testimony whereof, I have subscribed 85 my name.

JOHN ZANDER.
